COMPOSITE GROUND

George A. Knapp, Chicago, Ill., assignor to Knapp Brothers Manufacturing Company, Chicago, Ill., a corporation of Illinois

Application August 19, 1933, Serial No. 685,841

3 Claims. (Cl. 72—125)

The present invention has to do with a composite ground and the method of making the same, and refers more particularly to a ground useful in plastering and in terrazzo work.

At the present time, terrazzo work embodies the laying of floors and mop boards with plastic composition, which is plastic when laid and which is smoothed and, when hard, is smoothed by honing. In connection with such work, grounds are utilized to define block-like appearances in the floors, and, in plaster work, are utilized for edging and corners, and also as separation between the different materials.

An important feature of a ground, useful in terrazzo work, requires that the rib of such ground, be so constructed as not to be harmed by the honing process.

There are in use at the present time, grounds in which the ribs are made by folding parts of the material of which the ground is made, to form the upstanding ribs. In honing such ribs, sometimes the crests are ground off resulting in an imperfect ground and presenting rough and uneven surfaces at the joints.

The present invention has to do with a composite ground, and method of making, of such nature as to present ribs which are solid throughout, and which may be readily honed without destructive or dangerous effects, and which will provide smooth margins for the floors.

An object of the present invention is to provide a composite ground which may be economically manufactured and which at the same time provides a rib which may be honed without harmful results.

Another object of the invention is to provide a composite ground having the base member of thin inexpensive material such, for instance, as galvanized metal, and the rib of solid material, such as brass.

A further object of the invention is to provide a composite ground wherein the base members and rib members are separately manufactured and then fastened together in permanent relationship by a crimping action.

A still further object of the invention is to provide a novel method of making composite grounds.

Generally speaking the composite ground of the present invention contemplates a base member, which is perforated to form binding holes for the terrazzo or plaster material, and which is also perforated to receive lugs on the rib members whereby the rib members and base members

may be permanently fastened together by a crimping action.

The invention further contemplates the utilization of base members which are flat throughout the extent of the same and in which the rib members are crimped to the base members.

The invention further contemplates a novel manner of manufacturing the rib members with minimum waste material and at low manufacturing cost.

The above, other and further objects of the invention will be apparent from the following description, accompanying drawing, and appended claims.

The accompanying drawing illustrates a composite ground constructed in accordance with the principles of the present invention, and the views thereof are as follows:

Figure 1 is a fragmental vertical sectional view through a corner showing a floor and mop board of terrazzo, and with grounds, embodying the principles of the present invention, in place.

Figure 2 is a fragmental side elevational view of a rib of the present invention, and showing in section certain portions of the base member.

Figure 3 is an isometric view of a fragmental portion of a composite ground made in accordance with the principles of the present invention.

Figure 4 is an isometric view of a fragmental portion of a strip from which two of the ribs may be formed.

Figure 5 is an isometric view of fragmental portions of the base and rib members immediately prior to assembly.

The drawing will now be explained:

Referring to Fig. 1, a floor 1 of terrazzo supported on sub-structure 2 and the mop board 3 is illustrated as fashioned as terrazzo. The wall or plaster 4 is secured to studding 5 in any desirable manner.

There are, in this figure, shown two composite grounds of the present invention, designated at A and B. Each of these grounds is constructed in the manner hereinafter described.

A composite ground of the present invention contemplates a base member 6, which is flat throughout, and is fashioned from relatively inexpensive material such, for instance, as galvanized metal. The base member 6 is provided with a plurality of apertures 7 and 8 which serve as binding holes when the terrazzo material is applied over the grounds. In addition to the apertures 7 and 8, the base member 6 is pro-

vided with apertures 9 for a purpose to be later explained.

The rib member of the present invention, designated at 10, is made of strip brass material, or other suitable material and as herein illustrated 5 has formed in it cut-out portions such as arches 11 arranged at spaced intervals in the length of the rib member with the material of the member between such arches fashioned as lugs 12. At each end of every lug shoulders are formed 10 as at 13 which engage against the upper side of the base member 6 to limit the penetration of lugs 12 into the apertures 9 in the base member 6, when the rib member 10 is thereto applied.

Preferably the rib members are formed in the following manner. The strip of material, 14, of double the width of a single rib, is subjected to suitable machinery for punching out parts thereof to form elongated slots 15 and for forming 20 at the same time notches 16 at the extremities of the slots 15. The slots 15 and notches 16 are symmetrically formed with respect to the center line of the strip 14. When the notches and slots have been formed in the manner stated, the strip 14 is then severed longitudinally thereof along the line 17 thereby forming two similar rib members. The shoulders 13 of the rib members are indicated in Fig. 4 and the portion 25 of the rib member between the shoulders, designated at 18 provide the lugs 12 for entry into the apertures 9 of the base members 6. The provision of the slots, in the manner stated, provides, in the finished rib member, spaces 19 which serve as openings in the rib members 30 whereby when the ground is attached to a lath surface, it may be fastened in place by wire inserted through some of the holes 8 in the base 6 and the space 19 in the ribs.

Manufacturing the composition ground in the 40 manner described, enables manufacture thereof at an extremely low cost of material, and also for labor. The punching of the base member 6 is done by machinery and the formation of the slots 15 and notches 16 in the strip 14 is done 45 by machinery, as well as the splitting of the strip 14 to provide the finished rib members.

The grounds are assembled by inserting a rib member 10 in operative relation with the base member 6, with the lugs 12 of the strip member 50 extending through the apertures 9 in the base member. The rib member is pushed home until the shoulders 13 thereof abut the adjacent surface of the base member 6, whereupon the lugs 55 are subjected to swedging or crimping action to crimp the extremities of the lugs in such manner as to prevent separation of the rib member and the base member.

The rib members 10 in the manner described, 60 may be honed to smooth the floor 1, and thus offer no uneven or rough surfaces when honed. The rib members being made of soft material, such as brass, lend themselves very readily to the honing operation for finishing the terrazzo floor.

It will be observed that grounds of the present 65 invention may be economically manufactured, speedily assembled and are satisfactory in use.

The bases and ribs are separately made and 70 then assembled in permanent relation, by suitable pressure, crimping or swedging and the like, certain cooperating parts of the bases and ribs.

In plastering walls and laying terrazzo floors

and baseboards, the common practice is to plaster the walls first, so that dirt and plaster will not fall on the finished terrazzo floor. The plaster work must terminate at the point where the terrazzo begins.

One way to do this, at present, is to put up a temporary wooden strip, the plasterer finishes his work along this strip. Later, the strip is removed thus leaving a space below the plaster for the terrazzo layer. Such practice results in considerable 10 damage to the plaster when the terrazzo is laid for baseboards, requiring patching the plaster along the joint so made.

With the use of metallic grounds, the need for the temporary wooden strip is eliminated, as the metallic ground remains permanently in place and provides a fixed terminal point for the plasterer and also defines the top of the terrazzo baseboard.

Separation of the plaster and terrazzo materials 20 by such grounds serves another useful purpose. Usually Portland cement is employed in the terrazzo mix which is liable to stain the white plaster of the walls where the terrazzo and plaster meet. The use of grounds for separating these materials 25 prevents such staining.

The term "rib" has herein, for convenience, been applied to the upstanding part of the ground, yet it is to be understood that such term is used generically and not by way of limitation.

The invention has been described herein more or less precisely as to details, yet it is to be understood that the invention is not to be limited thereby, as changes may be made in the arrangement and proportion of parts, and equivalents 35 may be substituted, without departing from the spirit and scope of the invention.

The invention is claimed as follows:

1. A composition ground comprising in combination, a flat base perforated to provide means 40 to receive a rib, a rib fashioned to provide a plurality of arched cut-outs along one side and spaced lengthwise of the rib, portions of the rib between said arches constituting lugs for entering the receiving apertures in the base, said rib 45 having shoulders adjacent the lugs to limit penetration of the lugs into the base, and said lugs being swedged to lock the rib to the base, the arched cut-outs providing in the rib spaces for the reception of tie means for securing said ground against lath or like surfaces.

2. A composition ground comprising a flat base having apertures in it, a rib having longitudinally spaced cut-out portions cut in from one margin of the rib, the portions of the rib between the cut-outs constituting attaching lugs, and shoulders distinct from the rib margin adapted to limit penetration of the lugs into the base apertures.

3. In combination with wall or floor construction wherein different materials are used to finish such wall or floor, of grounds serving to separate such materials, said grounds comprising base members adapted to be embedded in the materials as laid and having ribs therein to serve to separate one mass of material from another, said bases and ribs having cooperating parts which are crimped or clamped to fasten the ribs and bases together, and said bases and ribs being provided with apertures to receive means for tying said grounds to lath or like surfaces.
